BOOK OF CARBON PAPERS

John B. Beach, Washington, D. C.

Application October 28, 1941, Serial No. 416,901

11 Claims. (Cl. 282—11)

This invention relates to carbon paper, and more particularly to a book of carbon papers from which a single sheet or a booklet containing a desired number of sheets can be detached easily for use as needed. It also relates to a book of alternate sheets of carbon paper and writing paper from which a booklet, containing a desired number of carbon sheets and writing sheets interleaved with one another, can be detached easily for use as needed, and, after use, the writing sheets can be detached from the booklet and withdrawn from between the carbon sheets with ease.

This application is a continuation in part of my copending application, Serial No. 335,175, filed May 14, 1940, for Book of carbon papers and container therefor.

It has heretofore been customary for carbon paper that is used for ordinary purposes to be supplied in loose-leaf form. When using such paper it is necessary to handle each sheet separately, and, when composing a pack of such carbon paper and stationery, great care is required to place each sheet of carbon paper and each sheet of stationery in proper alignment. This cannot be done easily, because carbon paper is generally not rigid.

In order to preserve used sheets of carbon paper in good condition for future use they should be placed one upon another in alignment before they are stored. It is not easy, however, to align them and keep them that way when they are handled. Consequently, they often get into a disorderly and unwieldy heap that results in their becoming wrinkled and dog-eared, and they cease to be useful sooner than they would if they were properly stored in a neat and orderly pack. Moreover, very thin sheets of carbon paper, which are preferred to thicker sheets when many copies are to be made, are easily blown about with the slightest movement of the air, making it very difficult and annoying to interleave them with sheets of paper, or to arrange them neatly for safekeeping after use.

The principal object of this invention is to provide means whereby many of the above-mentioned difficulties and disadvantages may be overcome.

One of the objects of the invention is to provide a pack of carbon papers in which each leaf is bound to the next leaf in such a way as to form a book, from which a single sheet or a desired number of sheets bound together as a booklet may be detached for use as needed. A plurality of sheets of carbon paper that are bound together at one end to form a booklet are easier to interleave with sheets of stationery, and to keep in neat condition after use, than loose-leaf sheets.

Another object of the invention is to provide a pack of alternate sheets of carbon paper and writing paper in which each sheet is bound to the next sheet in such a way as to form a book, from which a desired number of carbon sheets and writing sheets, interleaved with one another and bound to each other as a booklet, may be detached for use as needed, and, after use, the writing sheets may be detached easily from the booklet and withdrawn from between the carbon sheets.

Another object of the invention is to provide a pack of alternate sheets of carbon paper and writing paper in which each sheet is bound to the next sheet in such a way as to form a book, from which a desired number of carbon sheets and writing sheets, interleaved with one another and bound to each other as a booklet, may be detached for use as needed, and, after use, the writing sheets may be detached easily from the booklet and withdrawn from between the carbon sheets. This form of the device is preferably used with the so-called "one-run" carbon sheets that are intended for use once only and are then thrown away.

When "one-run" carbon paper is used in this form of my invention, one of the objects of the invention is to make it unnecessary for the operator to interleave sheets of writing paper with carbon sheets; the writing sheets that are intended to receive the carbon impressions are already interleaved with the carbon sheets, and all that the operator needs to do is to place a sheet of writing paper, which is intended to receive the original writing, on top of a booklet after it has been severed from the pack. Moreover, another object of this form of my invention is to make it unnecessary for the operator to exercise care in handling a pack of alternate sheets of carbon paper and writing paper to see that they do not slip out of register with one another, because the writing sheets and carbon sheets are bound together in register and cannot slip apart accidentally.

Another object of the invention is to provide a book of carbon papers of the type herein characterized which may also have the edges of the leaves opposite the bound edges staggered, or provided with notches, stiffened tabs, or tabs in the nature of index tabs so as to facilitate the handling of each leaf of the book, or of a booklet that has been detached from it.

Still another object of the invention is to provide a book of carbon papers and a book containing alternate sheets of writing paper and carbon paper, of the type herein characterized, which may also have one or both corners of the edges opposite the bound edge of the carbon sheets notched, to facilitate the removal of writing sheets that are interleaved with the carbon sheets.

With the above primary and other incidental

objects in view, as will more fully appear in the specifications, the invention consists of the features of construction, the parts and combinations thereof, or their equivalents, as hereinafter described and set forth in the claims.

Referring to the accompanying drawings wherein is shown the preferred, but obviously not necessarily the only form of the embodiment of the invention;

Fig. 1 is a plan view of a book of carbon papers;

Fig. 2 is an enlarged sectional view taken in the direction of the arrows on the line II—II of Fig. 1, illustrating one construction of the bond;

Fig. 3 is a perspective view illustrating the manner in which several sheets of carbon paper may be detached as a booklet from the book of carbon papers;

Fig. 4 is a perspective view of a fragment of a book of carbon papers that has one corner notched;

Fig. 5 is an enlarged sectional view, taken in the direction of the arrows on the line V—V of Fig. 1, showing a book of carbon papers that has staggered edges;

Fig. 6 is a plan view of a book of carbon papers that has uncarbonized marginal ends and two corners notched;

Fig. 7 is a perspective view of a fragment of a book of carbon papers that has indexed edges;

Fig. 8 is a fragmentary sectional view taken in the direction of the arrows on the line VIII—VIII of Fig. 7;

Fig. 9 is a perspective view of a fragment of a book of carbon papers that has notched edges;

Fig. 10 shows a sheet of carbon paper, weakened along a line parallel with and a short distance from one edge by means of perforations, for use when the bond is constructed as shown in cross section in Fig. 11.

Fig. 11 is an enlarged sectional view similar to that shown in Fig. 2, showing an alternate construction of the bond.

Fig. 12 is a diagrammatic sectional view showing the arrangement of a booklet of carbon paper interleaved with sheets of writing paper and located around the platen of a typewriter;

Fig. 13 is a plan view of a modified form of the invention showing a book comprising alternate sheets of carbon paper and writing paper;

Fig. 14 is an enlarged sectional view taken in the direction of the arrows on the line XIV—XIV of Fig. 13, showing one construction of the bond;

Fig. 15 is an enlarged sectional view similar to that shown in Fig. 14, showing another construction of the bond;

Fig. 16 is an enlarged sectional view similar to that shown in Fig. 14, showing still another construction of the bond;

Fig. 17 is an enlarged sectional view similar to that shown in Fig. 14, showing yet another construction of the bond;

Fig. 18 is a perspective view of the device shown in Fig. 13, illustrating the manner in which the writing sheets may be detached from the booklet and withdrawn from between the carbon sheets.

Referring more specifically to the drawings, in which like numerals refer to like parts throughout;

The numeral 1 indicates a book of carbon papers comprising a plurality of sheets of carbon paper 2 arranged in register with each other, with all of the carbonized surfaces facing the same direction. The sheets 2 are held together

adjacent one edge by a suitable bond, which may take a variety of forms as hereinafter explained in more detail.

The bond has a resistance to severance that exceeds the stresses resulting from normal handling of the sheets but that is exceeded by the stress resulting when any two contiguous sheets are grasped at their edges adjacent the bond and pulled away from each other by a peeling or stripping action. In other words, the bond is sufficiently strong to prevent accidental separation of the sheets during ordinary or normal handling of them, but at the same time it has a severability that permits relatively easy separation of the sheets in the manner mentioned.

Because the bond will withstand normal handling conditions and yet permit ready separation of any two contiguous sheets when they are peeled or stripped apart, a group of sheets of carbon paper of any desired number may be detached as a unit or booklet from the main book, and the sheets in the booklet will remain attached to each other, and the sheets in the main book will remain attached to each other, after the booklet has been severed from the book.

The bond may be formed in any manner that meets the above-mentioned requirements. Two means of constructing the bond are shown as examples. One is illustrated in Figs. 1, 2, 3, and 6, and the other in Fig. 11.

The bond 3, shown in Figs. 1, 2, 3, and 6, comprises an adhesive that meets the above-mentioned requirements of the bond. Suitable adhesives comprising materials of many different kinds may be used to form this type of bond, when prepared in conformity with a knowledge of the adhesive art to meet the above-mentioned requirements. Preferably, any adhesive used should be flexible to a degree and normally untacky. Generally, it may be said that the adhesives used should not possess such great adhesive strength that they have a tendency to resist severance to the extent of damaging the sheets while they are being severed from one another. On the other hand, the adhesives used should not be so brittle, or possess such slight adhesive strength that they have such a low resistance to severance that they will not withstand severance when subjected to the stresses resulting from normal handling of the sheets. While I do not wish to limit the scope of the invention to any particular kind of bond or adhesive so long as it meets the above-mentioned requirements, I at present prefer to make the bond 3 of a wax-like substance, such as a natural or synthetic wax, because it is inexpensive and can, in most instances, be used even where the portion of the carbon sheet to be bonded is impregnated with carbon, whereas certain other materials are less satisfactory unless the portion of the sheet to be bonded is devoid of carbon. I have found that paraffin wax is especially well adapted to form the bond, and, because it is relatively inexpensive and easily used, the book can be manufactured at little cost by using it.

If desired, the adhesion between contiguous sheets may be increased if the portion of the sheets that is to receive the adhesive is provided with apertures at spaced intervals so as to permit the adhesive to extend through the apertures to the next contiguous sheet. Such apertures would be in addition to the apertures 4 that may be provided for a purpose explained more fully below, so that they may, or may not, as desired, be

arranged to offset one another in alternate sheets when the book is composed.

If a desired bonding material does not have an affinity for the materials forming the carbonized surface of the carbon paper used, the portion of the carbon sheets that is to be bonded may be devoid of carbon. Thus, permitting, a wider range of adhesives to be used to form the bond.

A suitable bond may also be made as illustrated in cross-section in Fig. 11. There the carbon sheets 2' are weakened by perforations, or other suitable means, along a line parallel with, and a short distance from, the end of the sheet, in the manner shown at 10 in Fig. 10. The marginal end 11 of the carbon sheets that is set off by the perforations is then folded along the perforations and firmly fastened, by means of an adhesive 12 possessing substantial adhesive strength, or by other suitable means, to the back of the adjacent sheet of carbon paper, so that the perforations 10 in one sheet are adjacent those of the next sheet, as shown in cross section in Fig. 11. Thus, a bond is formed that resists severance during conditions of normal handling, but may be readily severed between any two contiguous sheets by stripping or tearing along the perforations.

If it is desired to use the book of carbon papers in connection with one form of the device shown and claimed in my copending application, Serial No. 335,175, filed May 14, 1940, referred to above, apertures may be provided at the edge of the book adjacent the bond, as indicated at 4.

When it is desired to use some of the carbon paper from the book 1, the number of sheets of carbon paper that are desired for the manifold writing are counted off, and, as a unit, they are severed from the book by peeling them off somewhat in the manner illustrated in Fig. 3. The sheets that are thus detached from the book remain attached to each other, by means of the bond, in the form of a booklet of carbon papers 13, wherein the sheets remain in register with each other and may be handled easily as a unit. The booklet may be placed on a flat surface, and sheets of writing paper interleaved with the sheets of carbon paper in the usual manner. This task is facilitated by the fact that the carbon sheets, being bound together adjacent one edge, remain in register with one another without the need for careful placement by the operator, and are not easily set in unruly motion by slight movements of the air. The task of interleaving sheets of writing paper with the sheets of carbon paper in the booklet can be made even less difficult if the booklet is used with the device disclosed and claimed in my copending application, Serial No. 335,175, filed May 14, 1940, referred to above.

The assembled manifold pack may be inserted in a typewriter in the usual manner, but the edge that has the free edges of the booklet of carbon papers should be inserted first, so that, as shown diagrammatically in Fig. 12, when the packet 14 has been drawn around the platen of a typewriter 15 the free edges will be at the top, as shown at 16, allowing easy access to each sheet of stationery for the purpose of making erasures or corrections.

After the manifold writing has been finished, the sheets of stationery may be removed easily from between the sheets of carbon paper by taking hold of the bound end of the booklet of carbon paper with one hand and shaking it so that the sheets of stationery will be released and fall

into the other hand. A more desirable means of removing the sheets, however, may be supplied if one or more of the corners of the free edges of the book is notched as indicated at 5 and 5' in Figs. 4 and 6, respectively. In that case, the bound end of the booklet may be held in one hand and the sheets of stationery may be held by the thumb and forefinger of the other hand at one of the notches 5 or 5', and the sheets of stationery may thus be pulled easily from between the leaves of the booklet.

If desired, the book of carbon papers may be composed of sheets of carbon paper with the bound edge or margin and the opposite edge or margin uncarbonized, as shown at 7 and 8 on the book 1, in Fig. 6. In this form, the corners of the unbound margin may be notched, as shown at 5', to permit easy withdrawal of the sheets of stationery from between the leaves of carbon paper, and to permit a booklet of carbon papers of this design to be used on the device shown in my copending application, Serial No. 335,175, filed May 14, 1940, referred to above, in the manner therein described.

If desired, in order to make it easy for the operator to take hold of one leaf of a book of carbon papers at a time, many means might be provided, and a few are illustrated in Figs. 5, 6, 7, 8, and 9. The margins 7, in Fig. 6, that are uncarbonized may be stiffened. The free edges of the book may be staggered as shown at 6 in Fig. 5, or they may be cut so as to offset one another in the manner of index tabs, as shown at 7' in Figs. 7 and 8; they may be notched in such a way that the notches of one sheet are adjacent to an unnotched portion of the adjacent sheets when the book is bound, in the manner shown at 17 in Fig. 9. Many other ways could obviously be suggested, but it is thought that these are sufficient for the purposes of illustration.

In the modified form of the invention, illustrated in Figs. 13 through 18, the numeral 19 indicates a pack or book of alternate sheets of carbon paper 2 and writing paper 20, arranged in register with each other. All of the carbonized surfaces 21 of the carbon sheets face the same direction, and, preferably, the first sheet at the top of the pack is a carbon sheet, with its carbonized surface facing down, in contact with the adjacent writing sheet, and the last sheet at the bottom of the pack is a writing sheet, so that for each writing sheet in the pack there is a corresponding carbon sheet with its carbonized surface adjacent the writing sheet. The sheets are held together adjacent one edge by a suitable bond, which may take a variety of forms as hereinafter explained in more detail. Preferably, each sheet of carbon paper is notched at one of its free corners, as shown at 5, exposing a corner of the sheets of writing paper.

The bond has a resistance to severance that exceeds the stresses resulting from normal handling of the sheets but that is exceeded by the stress resulting between any two contiguous sheets when they are grasped at their edges adjacent the bond and pulled away from each other by a peeling or stripping action. The resistance of the bond to severance is also exceeded as between any writing sheet and the adjacent carbon sheets, but is not exceeded as between said adjacent carbon sheets, when the writing sheet is grasped at its unbound end and pulled or jerked away from the bond. In other words, the bond is sufficiently strong to prevent acci-

dental separation of the sheets during ordinary or normal handling of them, but at the same time it has a severability that permits relatively easy separation of the sheets in the manner mentioned.

Because the bond will withstand normal handling conditions and yet permit ready separation of any two contiguous sheets when they are peeled or stripped apart, a group of alternate sheets of carbon paper and writing paper of any desired number may be detached as a unit or booklet from the main pack or book, and the sheets in the booklet will remain attached to each other, and the sheets in the main book will remain attached to each other, after the booklet has been severed from the book.

Since the bond will withstand normal handling conditions and yet permit the writing sheets to be separated from the carbon sheets by grasping the writing sheets at their unbound end and pulling or jerking them away from the bond, a booklet that has been severed from the book may be used for duplicate writing, and, while that is being done, the carbon sheets and the writing sheets will remain attached to each other and stay in register, but, after the writing has been finished, the writing sheets may be severed easily from the carbon sheets and withdrawn from between them, without the carbon sheets being severed from each other.

The bond may be formed in any manner that meets the above-mentioned requirements. Two types of construction of the bond are shown as examples. One type is illustrated in Figs. 13, 14, 15, and 18, and the other type in Figs. 16 and 17.

The bond 22, shown in Figs. 13, 14, and 15, comprises an adhesive that meets the above-mentioned requirements of the bond. Suitable adhesives comprising materials of many different kinds may be used to form this type of bond, when prepared in conformity with a knowledge of the adhesive art to meet the above-mentioned requirements. Generally, the same adhesives that are suitable to form the bond 3, in the form of the invention described above and illustrated in Figs. 1, 2, 3, and 6, are also suitable for the bond 22. While I do not wish to limit the scope of the invention to any particular kind of bond or adhesive so long as it meets the above-mentioned requirements, I at present prefer to make the bond 22 of the same materials as described above for making the bond 3.

When the bond is formed as illustrated in Figs. 13, 14, and 15, the carbon sheets are longer than the writing sheets and extend beyond them, as shown in the enlarged cross sectional view in Fig. 14. The carbon sheets 2 are held together adjacent the edge that extends beyond the writing sheets by the bond 22, and the edge of each writing sheet that is adjacent the extended edges of the carbon sheets is held by the bond 22 to the carbon sheet that has its carbonized surface 21 in contact with the writing sheet. The writing sheets could, if desired, be bonded also to the carbon sheet that has its back or uncarbonized surface in contact with the writing sheet, but it is not preferable to do so, because, otherwise, when they are bonded only to the adjacent sheet of carbon paper that has its carbonized surface in contact with the writing sheet, it is impossible for the pack or book to be severed inadvertently in such a way that a writing sheet will be bonded to a carbon sheet that has its uncarbonized surface next to the writing sheet.

The portion of the edge of the writing sheets

that is held to the carbon sheets by the bond is relatively small compared with the portion of the edge of the carbon sheets that is held to the next carbon sheet by the bond, so that the writing sheets are less securely held to the carbon sheets than are the carbon sheets held to each other. Because of this, the bond has less resistance to severance between the writing sheets and the carbon sheets than between the portions of the carbon sheets that are bonded together.

10 In some cases, if the bond is formed of certain adhesives, it may be advisable, in order to prevent the bond from penetrating into the paper and rendering it transparent, to provide the edge 15 of the sheets of writing paper that is secured to the sheets of carbon paper by the bond with a suitable hardening or impregnating medium where it comes in contact with the bond, especially when the bond is composed of certain waxes, such as paraffin wax, or wax-like derivatives of the fatty acids or their esters. As such an impregnating, saturating or protective agent 20 a suitable paste or glue, dextrine and the like, may be used.

25 As mentioned above, if a desired bonding material does not have an affinity for the materials forming the carbonized surface of the carbon paper used, the portion of the carbon sheets that is to be bonded may be devoid of carbon. Thus, 30 permitting a wider range of adhesives to be used to form the bond.

35 When the bond is made of certain materials having little body, the thickness of the writing sheets cause the book to bulge or be thicker throughout the length of the writing sheets than it is at the portion of the bond where the carbon sheets extend beyond the writing sheets. For this reason, it may be desirable in some instances 40 to provide a separator 23 of approximately the same thickness as the writing sheets to fill the space between the carbon sheets where they extend beyond the writing sheets and are bonded together. The separator may be formed in any suitable manner. In Fig. 15 it is illustrated at 45 23 as being formed from the folded, extended end of the carbon sheet, but it may, of course, be formed by a strip or ribbon of paper having approximately the same thickness as the sheets of writing paper used.

50 A suitable bond may also be made as illustrated in cross section in Fig. 16. There the carbon sheets 2' are longer than the writing sheets 20' and are weakened by perforations, or other suitable means, along a line parallel with, and 55 a short distance from, the end of the sheet, in the manner shown at 10 in Figs. 10, 16, and 17. The writing sheets 20' are similarly weakened by perforations, or other suitable means, along a line parallel with, and a short distance from, the end of the sheets in the manner shown at 24. 60 The marginal end 11 of the carbon sheets that is set off by the perforations 10 is folded over along the perforations and firmly fastened, by means of an adhesive 25 possessing substantial adhesive strength, or by other suitable means, 65 to the marginal end 26 of the writing sheet that is set off by the perforations 24. The other side of the marginal end 26 of the writing sheet is then firmly fastened to the next carbon sheet adjacent and below the perforations 10 of that carbon sheet. If desired, as illustrated in cross section in Fig. 17, the marginal end 26 of the writing sheet could be firmly fastened to the carbon sheet, adjacent and below the perforations 10 of that sheet, and the marginal end 11

of that carbon sheet could be folded over the marginal end of the writing sheet and securely fastened to the next carbon sheet, adjacent and below its perforations. In any event, the carbon sheets should be so placed with relation to the writing sheets and the perforations of the carbon sheets that the carbonized surface 21 of the carbon sheets will be in contact with the writing sheet to which that carbon sheet is firmly fastened. In other words, the carbon sheets and writing sheets should not be arranged, with relation to the perforations 10 of the carbon sheets, so that the perforations 10 will be located between a writing sheet and the carbonized surface of the carbon sheet that is in contact with that writing sheet.

A booklet of alternate sheets of carbon paper and writing paper that has been severed from the book is ready for duplicate writing, except that the sheet that is intended to receive the original writing must be placed on top of the first sheet of carbon paper in the booklet. After the duplicate writing has been finished, the writing sheets may be severed from the carbon sheets and withdrawn from between them by pulling them at the corner exposed by the notches 5 in the carbon sheets, in the manner illustrated in Fig. 18.

From the above description it will be apparent that there is thus provided means of the character described possessing the particular features of advantage enumerated above as desirable, but which obviously is susceptible of modification in form, proportions, detail construction and arrangement of parts without departing from the principle involved or without sacrificing any of its advantages.

While the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims. The term "carbon paper," as used in this application is intended to include all classes of transfer paper suitable for such purposes.

I claim:

1. An article of manufacture comprising a plurality of sheets of carbon paper and securing means that holds said sheets together adjacent one edge, said securing means having a resistance to severance that exceeds the stresses resulting from normal handling of said sheets but a severability that enables any two contiguous sheets to be separated, whereby groups of sheets of any desired number may be detached as units while the sheets of each group remain secured to each other in said group.

2. A book of carbon papers comprising a plurality of sheets of carbon paper held together adjacent one edge by means of wax that is severable between any two contiguous sheets, whereby groups of sheets of any desired number may be detached as units while the sheets of each group remain attached to each other in said group.

3. An article of manufacture comprising a plurality of sheets of carbon paper held together adjacent one edge by a bond having a resistance to severance that exceeds the stresses resulting from normal handling of said sheets but a severability that enables any two contiguous sheets

to be separated, whereby groups of sheets of any desired number may be detached as units while the sheets of each group remain attached to each other in said group.

4. An article of manufacture comprising a plurality of sheets of carbon paper held together adjacent one edge by a bond having a resistance to severance that exceeds the stresses resulting from normal handling of said sheets but a severability that enables any two contiguous sheets to be separated, whereby groups of sheets of any desired number may be detached as units while the sheets of each group remain attached to each other in said group; said bound end being provided with apertures, whereby the book may be suspended on a holder to facilitate interleaving sheets of carbon paper with sheets of writing paper.

5. An article of manufacture comprising a plurality of sheets of carbon paper held together adjacent one edge by a bond having a resistance to severance that exceeds the stresses resulting from normal handling of said sheets but a severability that enables any two contiguous sheets to be separated, whereby groups of sheets of any desired number may be detached as units while the sheets of each group remain attached to each other in said group; said bound edges being provided with means to facilitate the separation of said sheets in groups of any desired number.

6. An article of manufacture comprising a plurality of sheets of carbon paper having at least one edge devoid of carbon and a bond that holds said sheets together adjacent an edge that is devoid of carbon, said bond having a resistance to severance that exceeds the stresses resulting from normal handling of said sheets but a severability that enables any two contiguous sheets to be separated, whereby groups of sheets of any desired number may be detached as units while the sheets of each group remain attached to each other in said group.

7. An article of manufacture comprising a plurality of sheets of carbon paper, arranged in alignment with each other so as to form a pack in which all of the carbonized surfaces face the same direction, held together adjacent one edge by a bond having a resistance to severance that exceeds the stresses resulting from normal handling of said sheets but a severability that enables any two contiguous sheets to be separated, whereby groups of sheets of any desired number may be detached as units while the sheets of each group remain attached to each other in said group.

8. An article of manufacture comprising two or more sheets of carbon paper held together adjacent one edge by an adhesive material having adhesion that exceeds the stresses resulting from normal handling of said sheets but is severable between any two contiguous sheets by peeling said sheets apart.

9. A book of carbon papers comprising a plurality of sheets of carbon paper held together adjacent one edge by an adhesive material having adhesion that exceeds the stresses resulting from normal handling of said sheets but a severability that enables any two contiguous sheets to be peeled or stripped apart, whereby groups of sheets of any desired number may be detached as units while the sheets of each group remain attached to each other in said group.

10. An article of manufacture comprising a plurality of sheets of carbon paper and securing

means that holds said sheets together adjacent one edge, said securing means having a resistance to severance that exceeds the stresses resulting from normal handling of said sheets but a severability that enables any two contiguous sheets to be separated, said securing means comprising the folded edge of one sheet securely fastened adjacent the folded edge of the next sheet, and being weakened along its fold, whereby groups of sheets of any desired number may be detached as units while the sheets of each group remain secured to each other in said group.

11. An article of manufacture comprising a plurality of sheets of carbon paper and securing means that holds said sheets together adjacent one edge, said securing means having a resistance to severance that exceeds the stresses resulting from normal handling of said sheets but a severability that enables any two contiguous

10 sheets to be separated; each carbon sheet having attached to it, contiguous its carbonized surface and adjacent said securing means, a writing sheet; said writing sheet being held to said 5 carbon sheet by a bond having a resistance to severance that exceeds the stresses resulting from normal handling of said sheets but that is exceeded by the stress resulting when said writing sheet is pulled at its free end away from the bond; whereby groups of sheets of any desired number of carbon sheets and a like number of writing sheets attached to them may be detached as a unit while the carbon sheets of each group remain attached to each other in said group, and the writing sheets may be withdrawn from between the carbon sheets by pulling them at their free ends away from said bond.

JOHN B. BEACH.
